TRANSPARENT AIR FILTERING MASK

Robert A. Stegmon, 2151 NE. 124th St.,
Miami, Fla. 33156

Filed Jan. 8, 1973, Ser. No. 321,638

Term of patent 14 years

Int. Cl. D29—02; D24—99

U.S. Cl. D83—1 K

FIG. 1

FIG. 2

FIG. 3

FIG. 5

FIG. 4

FIG. 1 is a front elevation of a transparent air filtering mask, showing my new design;

FIG. 2 is a side elevation thereof;

FIG. 3 is a top plan view thereof;

FIG. 4 is a rear elevation thereof; and

FIG. 5 is a bottom plan view thereof.

I claim:

The ornamental design for a transparent air filtering mask, as shown.
